UNITED STATES PATENT OFFICE.

LOUIS KESSLER, OF CHICAGO, ILLINOIS, ASSIGNOR TO J. S. BEAUDRY, OF CHICAGO, ILLINOIS.

STORAGE-TANK FOR EXPLOSIVE LIQUIDS.

973,440.

Specification of Letters Patent. Patented Oct. 18, 1910.

Application filed June 1, 1909, Serial No. 499,577. Renewed June 4, 1910. Serial No. 565,076.

To all whom it may concern:

Be it known that I, LOUIS KESSLER, a citizen of the United States, residing at Chicago, in the county of Cook and State of Illinois, have invented a new and useful Improvement in Storage-Tanks for Explosive Liquids, of which the following is a specification.

My invention relates to improvement in 10 storage-tanks, of either large or small size, used for containing volatile and highly explosive liquids such as gasoline, naphtha, benzine, and the like; and the object of my invention is to provide a tank for this purpose with means for effectually preventing 15 explosion of its contents by volatilization thereof under subjection to the action of heat, as in case of fire, or by ignition of gas escaping from the tank.

20 Referring to the accompanying drawings—Figure 1 is a view in vertical longitudinal section of a tank equipped with my improvement; Fig. 2 is a broken plan view of the end-portion of the tank showing the 25 safety-device with which it is equipped to afford my improvement; Fig. 3 is an enlarged view in vertical section of the safety-device taken at line 3, Fig. 2; Fig. 4 is a view in plan section of the safety-device 30 taken at line 4 on Fig. 3, and Fig. 5 is a bottom plan sectional view taken at line 5 on Fig. 3.

A tank 6 of any desired shape, though preferably of rectangular form, as shown in 35 the drawings, is provided at the bottom with a discharge or draw-off opening 7. On the inside of the tank this opening is covered with a wire-gauze screen 8, and to the outside thereof about the opening is secured a 40 nipple 9 to which may be connected a pipe, valve, or other device (not shown), for the purpose of conducting liquid from the tank. A flanged ring 10 provided with a threaded opening 11 is attached about its flange to 45 the top of the tank and a safety-device 12 having a hollow head 13 is secured to the tank by a threaded engagement of the head with the opening 11. From the head projects a downwardly extending annular 50 flange 14 having an opening 15 through it and to the flange is attached one end of a tube 16 equipped at its opposite end with a disk-shaped wire-gauze screen 17, which is preferably secured in position by being 55 clamped at its circumferential edge between

a ring 18 and a bead 19 formed on the tube, the ring being expanded into the bead. A series of holes 20 is provided through the base of the head (Figs. 3 and 5), and a wire-gauze screen 21 covers the holes for the purpose hereinafter explained. From the head and forming a part thereof, projects an externally threaded thimble 22 tightly fitting the head or otherwise firmly secured therein and a cap 23 formed with a series of openings 24 and a central orifice 25 is screwed upon the thimble. A vapor or exhaust-valve 26 provided with sealing disk 27, preferably of leather, is provided with a tubular depending stem 28. The disk 27 seats upon the cap to yieldingly close the openings 24 against ingress of air while permitting egress of gas from the tank as will presently appear. The stem 28 passes loosely through the orifice 25 and carries at its inner end a hollow flanged cap 29 which serves to confine a spring 30 interposed about the stem between it and the cap 23. A valve-seat 31 is formed in the outer end-portion of the stem 28 and a vent or air-intake valve 32 having an upper stem 33 and a lower stem 34 is yieldingly held by a spring 35, against the seat 31 for normally closing the passage through the tubular stem. The stems 33 and 34 are afforded bearings, respectively, in the 80 valve 26 and the cap 29 and are formed with flat faces to afford a passage for air along and between them and their bearings.

It is customary to use tanks of the present class with small vent-holes which are 90 ordinarily left open at all times for the purpose of permitting free ingress of air to the tank for replacing the liquid as it is consumed, and prevent air-binding of the contents. Great waste results from the continued escape, through the vent, of vapor from the contents of the tank. Besides such waste, there is the constant danger of explosion of the tank by the accidental ignition of the escaping gas. Furthermore, such 100 tanks are liable to explosion from other causes, particularly in case of fire from the heat thereof. When, from any cause, the contents become unduly heated, and the vent (having an unvarying area), is insufficient 105 to properly relieve the increasing pressure of accumulating gas generated from such cause, the tank will explode upon the pressure becoming excessive. With my improvement all danger of explosion is eliminated 110

and the loss through evaporation due to the escape of gas is prevented, save as the pressure is required to be relieved in case of emergency.

5 The tank as constructed is admirably adapted for use on automobiles but it is not limited to such use, since it may be used for general storage purposes.

10 The operation is as follows: Assuming the tank to be filled with gasoline or other highly explosive liquid, as the contents are withdrawn, a partial vacuum is produced in the tank which, when it overcomes the force of the spring 35, causes the valve 32 to open, thereby permitting air to enter past the valve and through the screen 21 and perforations 20 to replace the withdrawn liquid. The air within the tank is maintained at a pressure somewhat less than atmospheric pressure, which difference is represented by the force of the spring 35, with the result that the less quantity of air absorbs a less quantity of the contents and resulting in a consequent material saving 25 by preventing excessive evaporation. Upon the exposure of the tank to undue heat, causing pressure therein through the evaporation of its contents, the pressure will be relieved when it reaches a point in excess 30 of the force of the spring 30 by raising the valve 26 from its seat and allowing vapor from the tank to escape to the atmosphere

through the openings 20, screen 21 and holes 24 past the valve 26. Should the escaping gas by any possibility become ignited, the 35 flame will be checked from contact with the contents of the tank outside of the tube 16 by either the wire-gauze 21 or 17, thereby preventing the explosion of the tank. After the tank has become emptied, it may be 40 again refilled through the opening 11 upon first removing the safety-device 12.

What I claim as new and desire to secure by Letters Patent is—

In combination with a tank of the character described, a safety-device having a head provided with a plurality of holes and seating in said tank, a metal screen covering said holes, a tube extending from said head, a metal screen interposed in the passage 45 through said tube, a cap provided with a plurality of openings and a central orifice and removably secured on said head, a spring-seated exhaust-valve closing said openings and provided with a hollow stem 50 working in said orifice, a spring about said stem for closing the valve, a valve-seat and a spring-seated air-inlet valve within the stem, for the purpose set forth.

LOUIS KESSLER.

In presence of—
CHAS. E. GAYLORD,
L. G. KIRKLAND.
